Primary Examiner — Marissa J Cash*Assistant Examiner* — Rebecca Tsehay(74) *Attorney, Agent, or Firm* — Bryan Cave Leighton Paisner LLP(57) **CLAIM**

The ornamental design for an electronic vaporizer, as shown and described.

DESCRIPTION

FIG. 1 is a front perspective view of our electronic vaporizer;

FIG. 2 is a front elevational view thereof;

FIG. 3 is a rear elevational view thereof;

FIG. 4 is an elevational view of the right side thereof;

FIG. 5 is a top plan view thereof;

FIG. 6 is a bottom plan view thereof; and,

FIG. 7 is an elevational view of the left side thereof.

The broken lines in the drawings depict portions of the electronic vaporizer that form no part of the claimed design.

1 Claim, 6 Drawing Sheets# US D909,665 S
